Des. 233,774
Patented Nov. 26, 1974

233,774

END ATTACHMENT FOR LEATHER WATCH STRAPS

Paul Friedman, Pawtucket, and Maurice Udelson, Riverside, R.I., assignors to Brite Industries Inc., Providence, R.I.

Filed Dec. 11, 1972, Ser. No. 314,243

Term of patent 14 years

Int. Cl. D10—07
U.S. Cl. D45—4 E

FIG. 2

FIG. 3

FIG. 4

FIG. 1

FIG. 5

FIG. 1 is a top plan view of an end attachment for leather watch straps showing my new design;
FIG. 2 is a right side elevational view thereof;
FIG. 3 is a rear elevational view thereof;
FIG. 4 is a front elevational view thereof; and
FIG. 5 is a bottom plan view thereof.

We claim:

The ornamental design for an end attachment for leather watch straps, substantially as shown and described.
